US0D1088637S

(12) **United States Design Patent** (10) **Patent No.:** **US D1,088,637 S**
(45) **Date of Patent:** **** Aug. 19, 2025**

(54) **PILLOW**

(71) Applicant: **Hangzhou Superstring Network Technology Co., Ltd**, Hangzhou (CN)

(72) Inventor: **Wenjun Xu**, Hangzhou (CN)

(73) Assignee: **Hangzhou Superstring Network Technology Co., Ltd**, Hangzhou (CN)

(**) Term: **15 Years**

(21) Appl. No.: **29/992,526**

(22) Filed: **Mar. 10, 2025**

(51) LOC (15) Cl. **06-09**

(52) U.S. Cl.

USPC **D6/601**

(58) **Field of Classification Search**

(57) **CLAIM**

The ornamental design for a pillow, as shown and described.

DESCRIPTION

FIG. 1 is a front, left, top perspective view of a pillow, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 4;

FIG. 14 is an enlarged view of detail 14 in FIG. 5;

FIG. 15 is an enlarged view of detail 15 in FIG. 6;

FIG. 16 is a front, left, top perspective view of the pillow in an alternate configuration;

FIG. 17 is an enlarged view of detail 17 in FIG. 16;

FIG. 18 is a front, right, top perspective view of the Pillow in an alternate configuration; and,

FIG. 19 is an enlarged view of detail 19 in FIG. 18.

The dash-dot-dash broken lines are for notating enlarged views and form no part of the claimed design.
